Elwood W. Grushon, 3731 S. Sepulveda Blvd.,
Los Angeles, Calif.

Filed Sept. 4, 1962, Ser. No. 71,531

Term of patent 3½ years

(Cl. D74—1)

The broken lines showing of a cigarette lighter and pen in FIGURE 2 is for illustrative purposes only.

I claim:

The ornamental design for a combined cigarette lighter holder and pen holder stand, as shown and described.
